UNITED STATES PATENT OFFICE

2,048,120

CONVERTIBLE GARMENT

Harry Greenbaum, Kansas City, Mo.

Application October 23, 1933, Serial No. 694,821

5 Claims. (Cl. 2—212)

This invention relates to wearing apparel and has particular reference to a unique garment adapted for sports wear and the primary object of this invention is to provide such a garment wherein is provided means for converting the same into either one of two distinct types of costumes, one of which is particularly useful where sports such as tennis, bicycle riding, running, etc. are to be indulged in.

One of the important aims of this invention is the provision of a unique convertible garment that comprises two distinct parts, said parts being uniquely interconnected for assembly, all as more specifically hereinafter set down in the specification, referring to the accompanying drawing, wherein:

Figure 1 is a front elevation of a garment made to embody this invention.

Fig. 2 is a rear elevation of the same.

Fig. 3 is a front view of one unit of the garment alone.

Fig. 4 is a stretch-out plan view of another unit of the garment alone.

Fig. 5 is a front elevation of the unit shown in Fig. 3, but with a portion thereof turned down to illustrate structural details.

Fig. 6 is an enlarged, fragmentary, front view of the assembled garment, and,

Fig. 7 is an enlarged, fragmentary, detailed, sectional view taken on line VII—VII of Fig. 1.

A convertible garment embodying the features of this invention consists essentially of two units 10 and 12 respectively, the former being what is commonly called trunks, while the latter is an overlapping skirt that is detachably secured to the trunks 10 on a line positioned an appreciable distance below the belt 14 of trunks 10 which normally encircles the waist of the wearer. Trunks 10 have an upper portion 16 which merges into a lower portion 18 of two legs and this upper portion 16 is split downwardly or inwardly from the upper edge of portion 16 to a circumscribing line 20 extending around trunks 10 at a point adjacent the lower part of upper portion 16.

As illustrated in Fig. 5, the upper portion 16 is provided with overlapping margins 22 and 24 respectively, which are provided with buttons and button-holes 26 and 28 respectively, as illustrated in Figs. 1, 5, and 6. Ordinary belt loops 30 are provided to receive belt 14 and a suitable number of pockets 32 are arranged in both the back and front of trunks 10.

Skirt 12, when stretched out, is flat and formed as illustrated in Fig. 4. When the skirt circum-

about the legs of the wearer for use, it overlaps and a series of buttons 34 engage button-holes 36 in such a manner as to be in continuation of the series of buttons and button-holes 28 and 26 respectively that are disposed along the front and at one side of trunks 10.

To quickly place and remove skirt 12 in assembled relation with trunks 10, there is provided along the greater part of the length of the upper edge 38 of skirt 12, a continuous securing means 40 which is drawn into interengagement with coacting securing means 42 extending continuously around line 20 on trunks 10. This continuous fastening or securing means is well known in the commercial field and is sometimes called a "zipper" fastener. A slide 44 is employed to draw members 40 and 42 into locking engagement and it is necessary that some set point between trunks and skirt 10 and 12 respectively be established before the two aforesaid members can be quickly positioned together.

This invention contemplates, therefore, the provision of securing means 46 carried by trunks 10 which engage coacting securing elements 48 carried by skirt 12 at the upper edge thereof between the end of continuous securing means 40 and the proximo end of the skirt. These securing means 46 and 48 may be in the form of ordinary glove or snap fasteners and when the operation of bringing the skirt into engagement with the trunks is started, it is these members 46 and 48 that are first secured together. After this action, the ends of securing members 40 and 42 will register and slide 44 may be drawn around to completely traverse the circumscribing line 20 formed on trunks 10 and upon which is positioned the continuous securing means 42. Obviously, the length of continuous securing means 40 along the upper edge of skirt 12 is the same length as the distance around trunks 10 at circumscribing line 20, whereon is positioned the continuous securing means 42.

Securing means 42 and 40 on trunks and skirt 10 and 12 respectively are overhung by projected marginal edges 50 and 52 formed on trunks and skirt 10 and 12 respectively so that when the securing means made up of members 42 and 40 is in the interengaged position, it is partially hidden. Since this continuous securing means is of metal, it is obvious that the portion thereof which shows between the edges of margins 50 and 52 will create a decorative line extending around the hip line of the wearer. The auxiliary securing means made up of parts 46 and 48 insures quick attachment of skirt 12 to trunks 10 and because

the line of attachment between the units of the garment is appreciably below the waist line, it is possible to utilize pockets 32 and maintain the decorative effect of buttons 26 and belt 14 at all times, regardless of whether or not skirt 12 is being worn.

This convertible garment may be fashioned of fabric of suitable texture and color and the garment may be made in sizes as desired. It is understood that all such modifications and even structural changes might be practiced without departing from the spirit of the invention or scope of the appended claims.

Having thus described the invention, what is claimed as new and desired to be secured by Letters Patent is:

1. A garment of the kind described comprising trunks, a skirt; snap fasteners for releasably securing together the same; and continuous interengaging means on said trunks and skirt respectively to further secure together the two after said snap fasteners are functioning, said continuous, interengaging means having parts secured to the trunks along a circumscribing line spaced appreciably below the top thereof, and parts along the upper edge of said skirt, said parts having a slide member interconnecting the same and designed to interlock the parts as it is moved therealong.
2. A garment of the kind described comprising trunks; a skirt; means for releasably securing together the said trunks and skirt at a set point; and interengaging means on said trunks and along the upper edge of said skirt respectively to further secure together the two after the trunks and skirt have been secured together at said set point, said interengaging means extending continuously around said trunks and past the said releasable securing means at the said set point.
3. A garment of the kind described comprising trunks having an upper thigh-encasing portion; a continuous securing means extending around said trunks at the lower part of said thigh-encasing portion; an auxiliary securing means at a point beside said first mentioned continuous securing means; a skirt adapted to circumscribe the said trunks below the said upper thigh-

encasing portion thereof; a continuous securing means extending along the upper edge of said skirt for a greater part of its length to coact with said continuous securing means on the trunks to hold the garment assembled when worn; and securing means adapted to coact with the auxiliary securing means positioned on the upper edge of the skirt between the end of said continuous securing means thereon and the end of the upper edge of the skirt, said auxiliary securing means serving to hold the continuous securing means of trunks and skirt in proper relation as they are being brought together into complete securing position.

4. A garment of the kind described comprising trunks; a skirt; means for releasably securing together the said trunks and skirt at a set point; and interengaging means on said trunks and along the upper edge of said skirt respectively to further secure together the two after the trunks and skirt have been secured together at said set point, said interengaging means extending continuously around said trunks and past the said releasable securing means at the said set point, said skirt being flat in stretch-out and overlapping when secured to said trunks, said overlapping portions of the skirt having a series of interengaging buttons and button-holes adjacent the said releasable securing means.

5. A garment of the kind described comprising trunks; a skirt; means for releasably securing together the said trunks and skirt at a set point; and interengaging means on said trunks and along the upper edge of said skirt respectively to further secure together the two after the trunks and skirt have been secured together at said set point, said interengaging means extending continuously around said trunks and past the said releasable securing means at the said set point, said skirt being flat in stretch-out and overlapping when secured to said trunks, said overlapping portions of the skirt having a series of interengaging buttons and button-holes adjacent the said releasable securing means, said trunks having a series of interengaging buttons and button-holes in alignment with said series of the same on the skirt.

HARRY GREENBAUM.
